United States Patent Office

Des. 183,278
Patented July 29, 1958

183,278

LUGGAGE LOCK

Charles S. Gehrie, Montclair, N. J., assignor to Presto
Lock Co., Garfield, N. J., a limited partnership

Application January 10, 1958, Serial No. 49,184

Term of patent 14 years

(Cl. D50—7)

Fig. 1

Fig. 1 is a front face elevational view of a luggage lock, showing my new design;

Fig. 2 is a side edge elevational view of the same; and
Fig. 3 is a bottom end view of the luggage lock.

I claim:

The ornamental design for a luggage lock, as shown.
